TO SKINNER ENGINE COMPANY, OF ERIE, PENNSYLVANIA, A CORPORATION OF
PENNSYLVANIA.

STEAM-ENGINE VALVE-GEAR.

1,142,853.

Specification of Letters Patent. Patented June 15, 1915.

Application filed September 30, 1911. Serial No. 652,087.

To all whom it may concern:

Be it known that we, LE GRAND SKINNER and EDWIN F. WILLIAMS, citizens of the United States, residing at Erie, in the county 5 of Erie and State of Pennsylvania, have jointly invented certain new and useful Improvements in Steam-Engine Valve-Gear; and we do hereby declare the following to be a full, clear, and exact description of the 10 invention, such as will enable others skilled in the art to which it appertains to make and use the same, reference being had to the accompanying drawings, and to the letters of reference marked thereon, forming part 15 of this specification.

This invention relates to steam engine valve-gear and has for its object the construction and combination of mechanism whereby the movement of the engine valves 20 from a closed to an open position and from such open to a closed position is instantaneously accomplished, and whereby such instantaneous opening, and closing may be timed as desired with relation to the travel 25 of the piston to produce the desired pause in such open and closed positions.

Another feature of this invention is the provision on the upper ends of the valve-stems of adjusting mechanism, adapted to 30 be operated when the mechanism is in operation and the arrangement and location of the valve-gear on the top of the cylinder in such a manner that every part thereof is at 35 all times accessible for adjustment and repair.

Suitable mechanism whereby we accomplish these results is hereinafter fully set forth and explained and illustrated in the accompanying drawings in which:

40 Figure 1 shows a side view in elevation of an engine cylinder embodying my invention. Fig. 2 is a top or plan view of the same.

In these drawings A, is a steam engine 45 cylinder; B, the exhaust chamber, and C the steam-chest, all of usual construction.

In the ends of the exhaust chamber B, we mount exhaust valves B', preferably of the puppet type, communicating with the ends 50 of the cylinder in the usual manner, and in the ends of the steam-chest C, we mount inlet valves (not shown) of the like type, which communicate with the ends of the cylinder in the usual manner.

55 The valve-stem B², extends upward from

the valve, through the housing B³, and secured upon the upper end of the valve-stem B², there is a sleeve 2, on the lower end of which there is a radial flange 3, and on the upper end of said sleeve 2, there is a 60 yoke 4. In the top of the yoke 4, there are placed adjusting screws B⁵, having thereon lock-nuts B⁶.

On the housing B³, there are arms B⁴ B⁴, between which there is pivoted a bell-crank lever G, one of the arms of which extends into the yoke 4, when it engages the lower end of the adjusting screw B⁵. The opposite end g', of the bell-crank lever G, is provided with a roller g², as and for the purpose hereinafter set forth. For operating these bell-crank levers G, we provide on the top of the exhaust chamber a rock-shaft D, and on the top of the steam-chest a rock-shaft E. The rock-shaft D is provided with a downwardly 70 extending arm D', communicating with an eccentric rod F, and actuating the rock-shaft D; and the rock-shaft E is provided with a like downwardly extending arm E' 75 communicating with an eccentric-rod F' for operating the rock-shaft E. On the rock-shafts D and E are secured rock-arms H provided at their ends with cam-shaped surfaces h, having raised portions h' thereon, which cam-surfaces h, engage the rollers g² 80 on the ends of the arms g' on the bell-crank levers G, and as the end of the rock-arms H are depressed the parts h' of the cam-surfaces h operate on the rollers g² to operate 85 the bell-crank levers G to raise the valve-stems B² and C² as the case may be, and thereby open the valve B'. The inclination of the parts h' of the cam-surfaces h being such that their action on the bell-crank 90 levers G is practically instantaneous, so that the valves B' are instantaneously opened to their full capacity, and when the ends of the rock-arms H move upward the springs b 95 operate on the valve-stems B² and C² to instantly close the valves.

The closing action of the cam surfaces, h, and h', on the arms H, upon the valves B', however, is such that the valve is not permitted to drop with a hammer-like blow upon their seats; but instead the closing movement of the valves is controlled by the cam-surfaces h, and h', the surface h, remaining in contact with the roller g², in the end of the arm g', of the lever G, the adjusting screw B⁵, being for the purpose of 110

taking up lost motion between the valve-stem and the lever G. In this manner we are enabled to provide, quick acting valve mechanisms which by reason of their construction and arrangement are comparatively frictionless and require only a minimum amount of power to operate them.

Having thus described my invention so as to enable others to construct and utilize the same, what I claim as new and desire to secure by Letters-Patent is:—

1. The combination in an engine valve-gear, of a valve, a valve-stem extending upward therefrom, a sleeve rigidly secured upon the upper end of said valve-stem, a radial flange on said sleeve, a cylindrical housing inclosing said sleeve and flange, a spring on said sleeve between said radial flange and said cylindrical housing, a yoke on the upper end of said sleeve, arms on the side of said cylindrical housing, a lever pivoted upon said arms, one end of which extends into said yoke, and cam mechanism actuated by some moving part of the engine to operate said lever to control the opening and closing of said valve, substantially as set forth.

2. The combination in an engine valve-gear, of a valve, a valve-stem extending upward therefrom, a sleeve rigidly secured upon the upper end of said valve-stem, a radial flange on said sleeve, a cylindrical housing inclosing said sleeve and flange, a spring on said sleeve between said radial flange and said cylindrical housing, a yoke integral with said sleeve and an adjusting screw in said yoke, arms on the side of said cylindrical housing, a lever pivoted on said

arms one end of which extends into and engages the lower end of said adjusting screw, 40 and cam mechanism actuated by some moving part of the engine to operate said lever to control the opening and closing of said valve, substantially as set forth.

3. The combination of an engine cylinder, 45 a valve-stem housing thereon, a valve, a stem thereon, a spring within said housing operating to cause said valve-stem to seat said valve, and an operating device operating to cause said valve-stem to lift said 50 valve, substantially as set forth.

4. The combination of an engine cylinder, 55 a valve-stem housing thereon, a valve-provided with a stem which extends through said housing, a sleeve secured on the upper end of said valve-stem, a collar around said sleeve, a spring within said housing operating on said collar to seat said valve, an operating lever outside of said housing adapted to lift said valve, substantially as set forth. 60

5. The combination of an engine cylinder, a valve-stem housing thereon, a valve-stem within the housing, a yoke secured to the upper end of the valve-stem, means engaging said yoke for operating it in one direction and spring mechanism within the housing for operating the stem in the opposite direction, substantially as set forth. 65

In testimony whereof we affix our signatures, in presence of two witnesses. 70

LE GRAND SKINNER.
EDWIN F. WILLIAMS.
